UNITED STATES PATENT OFFICE.

PHILIPP RUDOLF AND JOHN AUGUST LUND, OF BATAVIA, ILLINOIS, ASSIGNEES TO
SPLITDORF ELECTRICAL COMPANY, OF NEWARK, NEW JERSEY, A CORPORATION
OF NEW JERSEY.

MAGNETO-DRIVING CONNECTION.

1,191,476.

Specification of Letters Patent. Patented July 18, 1916.

Application filed March 23, 1914, Serial No. 326,788. Renewed April 27, 1916. Serial No. 94,049.

To all whom it may concern:

Be it known that we, PHILIPP RUDOLF and JOHN AUGUST LUND, citizens of the United States, and residents of the city of Batavia, county of Kane, and State of Illinois, have invented certain new and useful Improvements in Magneto-Driving Connections, of which the following is a specification.

Our invention relates to connections for driving magnetos when used in conjunction with internal combustion engines, and the object of this improvement is to provide a simple and effective means whereby an acceleration of speed will be produced in the magneto in order to produce a hot spark for starting the internal combustion engine.

Other objects will appear hereinafter.

Our invention consists in the combination and arrangements of parts hereinafter described and claimed.

The invention will be best understood by reference to the accompanying drawing forming a part of this specification, and in which,

Figure 1 is an elevation of a connection embodying our invention, Fig. 2 is a section taken on line 2—2 in Fig. 1, and Fig. 3 is a view similar to Fig. 1, but showing certain portions in different positions.

The preferred form of construction as illustrated in the accompanying drawing comprises a driving gear 4 adapted to be connected in any suitable manner to the crank shaft of an internal combustion engine, not shown.

A hub 5 is provided with an extension 6 which provides a journal for the gear 4. The hub 5 is rigidly fixed on shaft 7 by means of a nut 8 pressing said hub against a washer 9 and the latter against a shoulder 10 on shaft 7. The shaft 7 represents the broken off end of a magneto armature shaft, the construction being such that gear 4 is permitted to rotate on journal 6 of hub 5. The hub 5 is provided with an annular recess 11 and in the recess 11 is another recess 12, the latter being a drill-hole in the bottom of recess 11. A corresponding drill-hole 13 is formed in gear 4 and a helical spring 14 is positioned in recess 11 with its

ends inserted in drill-holes 12 and 13. This construction establishes a resilient connection between driving gear 4 and hub 5, as will be readily understood. In the outer side of gear 4 is secured a pin 15, and on the periphery of hub 5 is a pin 16 adapted to be

engaged against pin 15 and resiliently maintained thereagainst by the tension of spring 14, the latter being placed in recess 11 under slight tension, the tension of spring 14 being sufficiently strong to cause gear 4 to drive hub 5 without disengaging pins 15 and 16. Also in the periphery of hub 5 is positioned a pin 17, the latter being provided with an inclined outer face and forms a stop by means of which rotation of hub 5 is temporarily locked by means of a catch 18. The catch 18 is pivoted as at 19 to a fixed member 20; the member 20 may be a portion of the magneto frame or any other suitable article. The catch 18 is made of a length 70 and disposed in a manner so that it may be rocked to inoperative condition by means of a weighted arm 21, the latter being pivoted at pivotal point 19 of catch 18, the weighted arm 21 being formed in a manner that when in the position indicated in Fig. 1, a shoulder 22 formed thereon rests on the cap 18 in a manner to maintain the latter in inoperative condition, and when the weighted arm 21 is manually moved to the position indicated in Fig. 3, shoulder 22 rests on a portion of catch 18 on the opposite side of its pivotal point causing the weight of arm 21 to move and maintain catch 18 in operative condition, the latter condition being a 85 position in which the catch will be engaged by a stop 17 upon rotation of hub 5.

Formed on the outer face, or secured thereto, of gear 4 is a cam member 23. The cam member 23 upon rotation of gear 4 engages the under side of catch 18 moving the latter upwardly and freeing stop 17 from said catch. This upward movement of catch 18 also moves the weighted arm 21 on its pivotal point to a position in which it maintains catch 18 out of operative condition. In operation, the gear 4 is constantly driven and is connected to the crank shaft of the internal combustion engine in any suitable manner. The hub 5 being connected with gear 4 by means of spring 14 is caused to rotate at the same rate of speed with gear 4 as long as catch 18 is in its inoperative position.

In starting the engine, the catch 18 is moved to operative condition by means of moving weighted arm 21 to its position indicated in Fig. 3, then upon turning the engine over until stop 17 is engaged by the catch 18. At this time hub 5 is locked and gear 4 con-

tinues to move until pin 15 reaches a position indicated at the dotted line position 15', as shown in Fig. 3 when cam surface 23 engages the under side of catch 18 moving the 5 latter to inoperative condition. Upon unlocking stop 17, the tension of spring 14 causes the hub 5 to be rotated at a high rate of speed until pin 16 again engages pin 15 or catches up with gear 4. This highly increased rate of speed of hub 5 and consequently shaft 7 causes the armature of the magneto to be rotated very fast, and produces a hot spark for igniting the first charges of fuel introduced into the engine to 10 effect starting thereof.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the 20 scope of the appended claims.

Having described our invention what we claim as new and desire to secure by Letters Patent is:

1. A device of the kind described comprising a driving element; a driven element mounted adjacent said driving element; a spring operatively connecting said driving and driven elements; a stop on said driven element; a catch movably mounted and 30 adapted to be moved into the path of said stop; a weight shiftably mounted on said catch and adapted to be manually shifted to maintain the latter in the path of said stop; and a cam carried by said driving element adapted to disengage said catch from said stop and shift said weight to maintain said catch out of the path of said stop, substantially as described.

2. A device of the kind described comprising a driving element; a driven element mounted adjacent said driving element; a spring operatively connecting said driving

and driven elements; a stop on said driven element; a catch pivotally mounted and adapted to be moved into the path of said stop; a weight shiftably mounted on said catch and adapted to be manually shifted to maintain the latter in the path of said stop; and a cam carried by said driving element adapted to rock said catch from engagement with said stop and shift said weight to maintain said catch out of the path of said stop, substantially as described. 50

3. A device of the kind described comprising a driving gear; a hub mounted adjacent said gear; a spring operatively connecting said gear with said hub; a stop on said hub; a catch pivotally mounted and adapted to be rocked into the path of said stop; a weight shiftably mounted on said catch and 55 adapted to be manually shifted to maintain the latter in the path of said stop; and a cam carried by said gear adapted to disengage said catch from said stop and shift said weight to maintain said catch out of the path of said stop, substantially as described.

4. A device of the kind described comprising a driving gear; a hub mounted adjacent said gear; a spring operatively connecting said gear with said hub; a catch pivotally mounted and adapted to be rocked into the path of said stop; a weight pivotally mounted on said catch and adapted to be manually moved to a position in which said catch will be maintained in the path of said stop; and a cam carried by said gear adapted to disengage said catch from said stop and rock said weight to a position in which the same will maintain said catch out of the path of said stop, substantially as described. 75

In testimony whereof we have signed our names to this specification in the presence of two subscribing witnesses.

PHILIPP RUDOLF.
J. AUGUST LUND.
